UNITED STATES PATENT OFFICE

DAVID H. ZELL, OF BROOKLYN, NEW YORK

DESIGN FOR A VANITY CASE

Application filed July 16, 1929. Serial No. 32,084. Term of patent 14 years.

To all whom it may concern:

Be it known that I, DAVID H. ZELL, a citizen of the United States, residing at Brooklyn, in the county of Kings and State of New York, have invented a new, original, and ornamental Design for Vanity Cases, of which the following is a specification, reference being had to the accompanying drawing, forming part thereof.

Fig. 2 is an edge view, and
Fig. 3 is an end elevation.

The dominant feature of my new design consists in the exterior contour or shape of the vanity case shown.

I claim:

The ornamental design for a vanity case, as shown and described.

DAVID H. ZELL.
